UNITED STATES PATENT OFFICE.

ALFRED BEAMER, OF SPOKANE, WASHINGTON, ASSIGNOR TO A. B. C. TRAIN OPERATING COMPANY, A CORPORATION OF ILLINOIS.

RAILWAY DESPATCH-CATCHER.

934,129.

Specification of Letters Patent. Patented Sept. 14, 1909.

Application filed May 9, 1908. Serial No. 431,941.

To all whom it may concern:

Be it known that I, ALFRED BEAMER, a citizen of the United States, residing at Spokane, in the county of Spokane and State of Washington, have invented certain new and useful Improvements in Railway Despatch-Catchers, of which the following is a specification.

The object of my invention is to provide means for delivering despatches to moving trains; and also means whereby a plurality of despatches, generally two, can be delivered to different parts of the same train, ordinarily one to the engineer on the locomotive and one to the conductor to be delivered at the caboose or rear car of a passenger train.

The nature of my invention and its several objects will appear more fully from the appended description and claims and the accompanying drawings.

In the drawings—Figure 1 is a diagrammatic view of a railway train with my invention applied thereto. Fig. 2 is a view 25 of the catcher in operative position. Fig. 3 is a detail view of part of the catcher. Fig. 4 is a detail view showing the catcher folded to an inoperative position against the side of the car. Fig. 5 is an enlarged view of 30 the holder for the hoops, showing a hoop in position. Fig. 6 is a fragmentary sectional elevation of part of the holder. Fig. 7 is a view of a mast holder with two hoops in 35 position, together with a view of part of a car with a catcher attached.

Generally speaking, my invention consists in providing means for detachably holding two hoops in position at different elevations at the side of a railway track, the 40 hoops having despatches secured thereto by a spring clamp or otherwise, and providing upon the locomotive and one of the cars of a train two projecting arms located at different levels in such manner that each arm will 45 seize and carry away one of the hoops with its attached despatch. As is well-known, train orders are delivered in duplicate, one to the engineer and one to the conductor. By 50 means of my invention, embodying the hoops at different elevations and the catchers on the locomotive and rear car at different elevations, despatches may be delivered to the engineer and conductor without the necessity of bringing the train to a stop.

55 The form of the hoop is clearly illustrated

in Figs. 5 and 7 of the drawings. It may be formed of wood bent into the form of a closed loop 1 having a projecting stem 2. The end of the wooden strip forming the loop may be secured to the central portion of 60 the strip by means of a nail or rivets 3. The projecting stem 2 is preferably circular in cross section, for the purpose of properly co-acting with the holder, and is tapered to a wedge shaped form at 4. For the purpose 65 of holding a despatch in place upon the hoop, I provide some form of spring clamp, preferably formed of wire, as indicated at 5. This clamp may be conveniently formed by wrapping the wire around the junction between the end of the wooden strip and the central portion thereof, and forming a projecting loop 6 adapted to be held by the spring tension of the wire against the wooden strip. The despatch is inserted by lifting 70 75 the wire loop, inserting the despatch beneath and permitting the loop to spring back to normal position.

The hoops above described are designed to be held upon a mast or other support 7 at the 80 side of a railway track, as illustrated in Fig. 7, the two hoops being held at different elevations. The holder wherein the hoops are secured is shown in the present instance as comprising a base plate 8 provided at its 85 upper and lower ends with yokes 9 having their outer ends spaced from the main body of the base plate. At their outer extremities the yokes 9 carry housings 10, which may consist of short sections of gas pipe provided at their outer ends with the usual caps 90 11. Inside of the housings 9 are plungers 12, which are impelled against the ends of the base plate by means of springs 13. Preferably, the plungers 12 are provided 95 with reduced stems 14 which pass through the centers of the springs and through apertures in the caps 11, thus forming guides for the plungers. The inner ends of the plungers are preferably rounded, as shown at 13, 100 for the purpose of facilitating the removal of the hoops when caught by the co-acting mechanism upon a passing train. The ends of the base plate 8 opposite the plungers 9 are preferably grooved, as shown at 14, in order 105 to provide a more secure seat for the stems 2 of the hoops. In order to additionally secure the hoops in place without obstructing their free removal, I provide leaf springs 15 secured to the inner faces of the yokes 9 and 110

having their free ends project over the grooves 14. The free ends of the springs 15 are adapted to be engaged by the wedge shaped end 4 of the stem 2 when the latter is inserted in place in the holder. From the foregoing, it will be apparent that the hoops 5 may readily be mounted in the holder by sliding them endwise, the tapered end 4 of the stem 2 serving to raise the plunger 13 10 and the spring 15.

The mechanism for removing the hoops from the holder consists essentially in an arm projecting diagonally forward from some part of the train, and having its end 15 so located that it will enter the center of the loop of the despatch hoop and remove the same from its holder. I have illustrated the 20 catcher as consisting of a base plate 16 provided at its back with a projecting arm 17 adapted to coact with a socket 18 of the form usually employed for attaching lamps and flags. In use, the base plate is designed to lie in a plane parallel to the side of the car or locomotive to which it is attached. 25 Pivoted to the base plate is the catcher arm 19. In the present instance I have shown the catcher arm as rigidly secured to a hinge plate 20 pivoted by means of the pin 21 to brackets 22 extending between the base plate 30 16 and a horizontal projection 23 extending forwardly therefrom. The base plate 16 is provided with an aperture 24 and with a lug 25 projecting rearwardly from a point at one side of said aperture. Pivoted to the lug 25 35 and extending forwardly through the aperture 24 is a latch 26 provided with a downwardly extending lip 27 adapted to engage the hinge plate 20 and to hold the same in vertical position, in which position the arm 40 19 will lie along the side of the car and in close proximity thereto, as illustrated in Fig. 4. Upon the rear of the plate 16 I provide a housing 28, for the purpose of inclosing a spring 29, the projecting end of which engages and normally holds in depressed position the latch 26. When approaching a station 45 where a despatch is to be delivered without stopping the train the latch 26 is raised and the arm 19 permitted to drop by gravity to the position illustrated in Fig. 2. In order to properly position the arm 19 when in its lowered position I provide an adjustable stop screw 30 threaded into an aperture in the horizontal projection 23, and 50 provided with a lock nut 24.

As illustrated in Fig. 1, the engineer's despatch catcher is secured to the side of the cab just beneath the arm rest and in position to engage the lower one of the hoops 60 upon the mast 7, and the conductor's catcher is located upon the rear corner of the caboose at such an elevation that it will engage the uppermost of the two hoops. The essential idea is, however, that the two catchers be 65 located at different elevations in order that

each of them may engage one of the hoops. In Fig. 7, the lower catcher is shown as secured to the rear of a passenger car, in which event the engineer's catcher would be located above and in position to engage the upper 70 hoop.

While I have illustrated and described one specific embodiment of my invention, it will be apparent that not all of the details described are essential.

What I claim and desire to secure by Letters Patent is:

1. In an apparatus of the class described, a car, a despatch catcher comprising a socket rigidly secured to the car, a support having a member 80 removably engaging said socket, a catcher arm pivoted to said support and movable from proximity to the car to a position projecting obliquely therefrom, and means mounted on the support for holding the arm in retracted position.

2. In an apparatus of the class described, a car, a support fixed thereto, an arm pivoted to said support, and a spring pressed latch mounted on said support and adapted 90 to engage said arm to hold it against movement.

3. In an apparatus of the class described, a support, a plate pivoted thereto, an arm secured to said plate, a lug upon said support adjacent an aperture therein, a housing 95 projecting from said support, a latch pivoted to said lug and projecting through said aperture, and a spring engaging said latch and housing, said latch being adapted to engage 100 said plate.

4. In an apparatus of the class described, a support, a plate pivoted thereto, an arm secured to said plate, an adjustable stop upon said support in operative relation to said 105 plate, a lug upon said support adjacent an aperture therein, a housing projecting from said support, a latch pivoted to said lug and projecting through said aperture, and a spring engaging said latch and housing, said 110 latch being adapted to engage said plate.

5. In an apparatus of the class described, a hoop holder, comprising a rigid base, and a spring pressed plunger opposed to said base.

6. In an apparatus of the class described, a grooved base, a round headed plunger, and a spring impelling said plunger toward said groove.

7. In an apparatus of the class described, 120 a grooved base, a plunger opposed to said base, a spring impelling said plunger toward said groove, and a spring fixed to said base and having its free end overlying said groove.

8. In an apparatus of the class described, a base plate having its ends grooved and lying in substantially horizontal planes at different elevations, and spring plungers 125 opposed to each of said grooves.

9. In an apparatus of the class described, a base plate having its ends grooved and lying in substantially horizontal planes at different elevations, spring plungers opposed to each of said grooves, and springs fixed to said base plate and projecting over said grooves.

10. In an apparatus of the class described, a grooved base plate, a spring pressed 10 plunger opposed to the groove in said base

plate, and a despatch hoop comprising a loop and a free end, said free end being held between said plunger and the groove in said base plate.

In testimony whereof, I have subscribed 15 my name.

ALFRED BEAMER.
